(57) **CLAIM**

We claim the ornamental design for a photo viewer, as shown and described.

DESCRIPTION

FIG. 1 is a front perspective view of a photo viewer.

FIG. 2 is a rear perspective view of the photo viewer illustrated in FIG. 1.

FIG. 3 is a front elevational view of the photo viewer illustrated in FIG. 1.

FIG. 4 is a rear elevational view of the photo viewer illustrated in FIG. 1.

FIG. 5 is a right side view of the photo viewer illustrated in FIG. 1.

FIG. 6 is a left side view of the photo viewer illustrated in FIG. 1.

FIG. 7 is a top plan view of the photo viewer illustrated in FIG. 1; and,

FIG. 8 is a bottom plan view of the photo viewer illustrated in FIG. 1.

The portions of the body of the photo viewer in broken lines are shown for illustrative purposes only and form no part of the claimed design.
